Ruth Busey
INVENTOR
BY Victor J. Evans

ATTORNEY

WITNESS: g. d. Wright

UNITED STATES PATENT OFFICE.

RUTH BUSEY, OF SEATTLE, WASHINGTON.

CAP FASTENER.

Application filed January 3, 1928. Serial No. 244,292.

This invention relates to apparel and particularly to head coverings.

The general object of the invention is to provide a fastener for securing a nurse's cap or the like to the head of the wearer, with the result that the use of pins and similar fastening means of like character can be dispensed with.

A further object of the invention is to provide a resilient fastener of the character as above set forth that is adapted to be detachably disposed in the front fold of a nurse's cap, so that the fastener will function to secure the cap to the wearer's head but will in no way detract from the appearance of the cap.

Another object of the invention is to provide a resilient fastener for securing a nurse's cap to the head of a wearer, that is simple in construction, inexpensive to manufacture, and efficient in operation and service.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a perspective view illustrating the application of one form of the cap fastener.

Figure 2 is a sectional view of the form as shown in Figure 1, with parts in elevation.

Figure 3 is a sectional view taken approximately on line 3—3 of Figure 2.

Figure 4 is a sectional view taken through a slightly modified form constructed in accordance with the form as shown in Figures 1 and 2.

Figure 5 is a perspective view of a further modified form.

Figure 6 is a sectional view taken approximately on line 6—6 of Figure 5.

Figure 7 is a front elevation of a further modified form.

Figure 8 is a sectional view taken on line 8—8 of Figure 7.

Figure 9 is an edge elevation of the form as shown in Figure 2.

Referring to the drawings in detail, the

letter A indicates a nurse's cap which is of the usual construction and includes a front strip which is folded so as to be disposed in superposed relation with respect to the body of the cap as shown.

The fastener which forms the subject matter of the present invention is adapted to be disposed between the front strip and the body so as to function to hold the cap upon the wearer's head but will be completely covered by the front strip as clearly shown in Figure 1.

In the form of the invention as shown in Figures 1, 2, 3 and 9 it will be noted that I have provided a tubular member 1 formed from resilient material and curved upon itself to follow the curvature of a person's head. Mounted for slidable movement in the tubular member and extending from the opposite ends thereof are adjusting pieces 2 which have their free ends curved upon themselves as at 3 so as to limit the movement of the pieces in the tubular member as will be apparent. The adjusting pieces are rounded in cross section to follow the cross sectional shape of the tubular member and due to the fact that they are slidably mounted in the tubular member they can be adjusted as desired so as to fit various sizes of caps.

In Figure 4 I have illustrated a slightly modified form of the construction as shown in Figures 1, 2, 3 and 9 and in this form it will be noted that the adjusting pieces which for distinction are indicated by the reference numeral 4, are flat, and are received for slidable movement in a covering 5 of rectangular shape in cross section. The function of the adjusting pieces 4 is similar to the adjusting pieces 2.

In Figure 5 I have illustrated another modified form of the invention which as shown includes a body 6 formed from resilient material and is flat as shown. The ends of the body 6 are curved upon themselves to provide protecting means 7.

In Figure 7 I have illustrated a further modified form of the invention, which is provided with a body 8 formed of resilient wire and has secured in any well known manner to its ends knobs 9 so that these ends will in no way effect the wearer or cause damage to the cap.

From the above description and disclosure

of the drawings it will be obvious that I have provided a fastener which may be easily and conveniently arranged with respect to a nurse's cap and the like for securing the same upon the head of a wearer and due to the construction of the forms as shown in Figures 1 to 3 inclusive as well as the resilient qualities of the form as shown in the remaining figures, the fastener may be adjusted so that it can be associated with various sizes of caps as well as to cause the cap to snugly engage the head of the wearer. The fastener may be made in small, medium and large sizes.

It is thought from the foregoing description that the advantages and novel features of my invention will be readily apparent.

I desire it to be understood that I may make changes in the construction and in the combination and arrangement of the several parts,

provided that such changes fall within the scope of the appended claims.

What I claim is:

1. The combination with a cap including a body and a front piece superposed with respect to said body, a resilient fastener adapted to be removably arranged between the body and front piece for the purpose of securing the cap to the wearer's head.

2. A cap fastener of the character described comprising a tubular member formed from resilient material, adjusting pieces mounted for slideable movement in said tubular member, protective means formed on the outer ends of said adjusting pieces, and said tubular member being curved upon itself to follow the curvature of a person's head.

In testimony whereof I affix my signature.

RUTH BUSEY.
